UNITED STATES PATENT OFFICE.

EDWARD T. CURRAN, OF DETROIT, MICHIGAN.

SPARK PLUG.

Application filed October 8, 1921. Serial No. 506,269.

To all whom it may concern:

Be it known that I, EDWARD T. CURRAN, a citizen of the United States, residing at Detroit, in the county of Wayne and State 5 of Michigan, have invented a certain new and useful Spark Plug, of which the following is a specification.

This invention is a spark plug, and, more particularly, a plug adapted for general application.

There are two distinct types of plug on the market at the present time, namely, those adapted for use under conditions of relatively low pressures and the heavy duty 15 type which are constructed much heavier and more substantial than the first type and are adapted for use in marine engines, aeroplane engines and other engines where the compression is high and the pressure of the 20 explosion is great. It is practically impossible to employ a low duty plug in a heavy duty engine for the reason that the plug, after a relatively short time, is invariably blown out or broken and rendered inoperative.

The main object of the invention is to provide a plug adapted for use for both heavy and relatively light duty engines, so constructed that it is not bulky or unwieldy, but 30 is, on the contrary, of relatively small size and proportions, but of maximum strength to withstand the force of compression or power of explosion in the associated cylinder.

This object is attained through the employment of novel plug structure and the efficient proportioning of the parts, so as to withstand maximum pressures without necessitating the making of these parts large 40 and bulky.

Another object of the invention is to so construct the plug that priming fluid or a decarbonizing fluid may be readily introduced into the associated cylinder through 45 the plug in a novel, expeditious and highly efficient manner and to permit also of the blowing out of oil or carbon deposits from the plug and associated cylinder through said plug. These features are accomplished 50 through the employment of novel valve structure and the plug is so constituted that in the event a priming fluid is introduced, no surplus priming will be entrained in 55 the plug in such manner that a rise in temperature of the plug will render the entrained or enclosed surplus fluid dangerous.

Other objects and advantages of the plug of this invention will be apparent from the hereinafter detailed description, from the drawing and from the appended claims.

While the plug may vary in form without departing from the present invention, it comprises, in one of its practical embodiments, a one-piece or integral shell, provided with a threaded nipple or shank adapted to 60 be received into the tapped hole of the engine and all of the plug parts are at least partially housed within this shell. The central electrode is carried by an insulating member, preferably of porcelain and this insulating member is seated within the shell on a valve seat member provided with an 65 upstanding tubular portion adapted to embrace that portion of the porcelain with which priming fluid or decarbonizing fluid 70 would be apt to come into contact.

By this construction, the porcelain is protected against cracking, due to unequal expansion, particularly when relatively cold water is introduced into the plug while 75 the plug is hot.

The novel form of tubular cylindrical valve cooperates with the valve seat and its interior constitutes a funnel shaped cup into which the priming or decarbonizing fluid 80 may be readily poured, thereby adapting this operation to be easily and expeditiously carried out.

The valve seat member, as well as the valve itself collectively cooperate with the shell to hold the porcelain in place, so that it cannot be blown out when subjected to high pressures. The grounded electrode of the plug is preferably formed integral with the shell, while the central electrode of the 90 plug is preferably swedged at its lower end to provide a cooperating plug point. The points of the plug may vary in shape, but, in practice, opposed knife edges are found to give very satisfactory and highly efficient 95 results.

Features of the invention, other than those specified, will be apparent from the hereinafter detailed description and claims, when read in conjunction with the accompanying 100 drawings.

The accompanying drawings illustrate one practical embodiment of the invention, but the construction therein shown, is to be understood as illustrative, only, and not as 110 defining the limits of the invention.

Figure 1 shows a plug embodying the

present invention, partly in elevation and partly in central section.

Figure 2 shows the plug elements dismantled; and,

5 Figure 3 is a section on the line 3—3 of Figure 1.

Referring to the drawings, 1 designates the shell of the plug and the shell is made somewhat longer than usual and is provided at its lower end with a threaded shank 2 adapted to be screwed into the tapped hole of a motor cylinder head for the purpose of mounting the plug on the motor in the usual manner. The exterior of the shell is provided with a polygonal portion 5 to permit of the application of a wrench thereto, so that the stem 2 thereby may be screwed tightly into the motor or moved therefrom.

10 The shell is provided interiorly at a point substantially midway between its top and bottom with a shoulder 3 and above this shoulder the shell is interiorly threaded as at 4. That portion of the shell below the shoulder 3 constitutes the plug chamber, 15 which is divided into upper and lower parts 6 and 7; and the lower part of the shell is preferably so constructed that the chamber 7 will taper upwardly through the formation of the wall of the threaded shank 2 with 20 a downward taper.

25 The central metallic electrode 8 of the plug extends entirely through the shell and beyond the upper end thereof and is enclosed for the greater portion of its length within an insulating member 9 preferably of porcelain. In practice, the porcelain is molded about the electrode 8 and thereafter baked so that the electrode is firmly embedded in the porcelain and becomes substantially homogenous therewith, thereby precluding the electrode from working loose within the porcelain and producing leakage through which compression might be lost.

30 The lower portion 10 of the insulating element 9 is preferably of substantially spherical contour and this portion 10 is surmounted by an enlarged cylindrical portion 11, which is, in turn, surmounted by a smaller cylindrical portion 12. The cylindrical portion 11 is of such size that it may be readily received into the upper portion of the shell 1 and come to a seat on a gasket 13 resting upon the shoulder 3. It is held in this position by a valve seat member 14. 35 This valve seat member 14 is in the form of a ring, the outer circumference of which is threaded to engage with the threads 4 of the shell and from the inner circumference of which extends an upstanding tubular sleeve 15. After the insulating member has been introduced into the shell and comes to a seat on the gasket 13, the valve seat member 14 is adapted to be screwed down into the top of the shell and comes to a seat on top 40 of the enlarged cylindrical portion 11 of the

insulating element. A gasket 16 is preferably interposed between these parts to preclude leakage of compression.

45 The upper face of the valve seat member 14 is provided with an annular groove or channel 17, preferably V-shaped in section and this channel forms a valve seat. With this valve seat 17 cooperates a tubular valve 18, the lower portion of which is exteriorly threaded to engage with the threads 4 of the shell and the upper portion 19 of which is polygonal to permit of the application of a wrench to the valve in order that it may be screwed down tightly upon the seat 17. The lower edge of the valve wall is bevelled both 50 interiorly and exteriorly so that the lower edge of such wall is substantially wedge shaped thereby enabling it to readily cooperate with the V-shaped seat.

55 It will be noted, however, that the taper of the valve is preferably less than the taper of the seat and this is the structure preferred, so that when the valve is screwed down tightly it will engage with the seat in two line contacts which assure a tight 60 liquid seal and also preclude the leakage of compression.

65 The interior of the valve 18 is substantially funnel shape and this configuration permits of the ready introduction of a priming or decarbonizing fluid into the plug. The fluid thus introduced into the interior of the valve 18 is adapted to find entrance into the associated cylinder by unscrewing the valve 18 to lift it from its seat. The liquid 70 is thus adapted to flow into the seat channel 17 downwardly from the base of which, at suitable intervals, circumferentially of the plug, extend passages 20. These passages 75 discharge the fluid into an annular channel 21 formed on the under side of the valve seat member 14. The liquid thus entering the channel 21 is adapted to flow through 80 passages 22, which are formed in the enlarged cylindrical portion 11 and which 85 serve to lead the liquid into the upper plug chamber 6, whence it flows through the lower plug chamber 7 into the associated cylinder. 90

95 In practice, the parts are preferably so assembled that the passages 22 are equal in 100 number to the passages 20 and are placed in alinement with said passages, so that there will be a substantially straight-through 105 flow of fluid from within the valve to within the plug chamber. This is of particular importance when it is desired to blow off carbon deposits from the interior of the associated cylinder or oil or carbon deposits from the interior of the plug or associated cylinder. To accomplish this, it is only 110 necessary to unscrew the valve 18 for the purpose of unseating the same and thereafter to run the engine, while the valve is 115 left open.

120 During the operation of blowing out for- 125

5 eign deposits in the manner described, the funnel shaped valve interior is found to be of considerable importance since its formation is such that there will be no back pressure and no possibility of depositing the blown off products on the interior of the valve. They will be blown free from the plug, leaving all parts of the plug clean.

10 I have hereinbefore referred to the up- standing tubular sleeve 15, which is formed integral with the valve seat member 14 and embraces the porcelain 9 to a point above the top of the valve member 18. I find that in practice this sleeve is of considerable practical importance since it serves to fully and efficiently protect the porcelain against breakage. This is particularly true when relatively cold water is introduced into the valve when the plug is hot, in which event, 20 if the water were to come into direct contact with the heated porcelain within the confines of the valve, the sudden cooling of the porcelain would be very apt to cause a breaking or cracking of the same. The sleeve 15, 25 however, has the further function of mechanically protecting the porcelain against breakage when subjected to sharp knocks, which may be imparted thereto by mechanics working on the associated engine.

30 I have furthermore referred to the upward taper of the interior of the threaded shank 2. This feature has been found of importance and utility in that the formation of the plug in this manner seems to produce a 35 scouring action of the gases entering the plug during its normal operation, the flow of which gases is caused by the explosion and compression of the motive fuel. The gases appear to flow into and out of the 40 plug chamber from the associated cylinder and exert a scouring action on the interior of the shell 1 and also on the lower ball shaped end 10 of the porcelain, and the depending central electrode and serves to keep 45 these parts free from oil or carbon deposits.

50 The sparking points of the plug of this invention may be constructed or formed in different ways, but a very practical construction is shown in the drawings. As shown, the grounded electrode 23 may be cast integral with the shell 1 and is preferably in the form of an inwardly projecting spur, the inner edge of which may be sharpened to a knife edge. The central electrode 8 may 55 be conveniently swedged at its lower end to provide one or more radially projecting sparking edges or points 24, the edges of which may be also sharpened to a knife edge.

60 In Figures 2 and 3 of the drawings, the central electrode is shown as provided with two sparking points or edges, only one of which is used at any one time, but in case one burns off, the electrode, together with

65 the porcelain 9 may be rotated, so as to present the other sparking point for cooperation with the grounded point 23. If desired, however, any number of sparking points may be provided on the central electrode and a corresponding number of integral spurs 23 70 may be formed on the shell.

75 It will appear from the foregoing specification that the shell has housed therein practically all of the operating parts of the plug and furthermore that the lower end of the shell is screwed into the engine cylinder, while the porcelain is locked against blowing out under high pressures not only by the valve seat member 14, but also by the valve 80 18. In other words, both the parts 14 and 18 are threaded directly into the shell and hold or back up the porcelain, so it cannot possibly be blown out when the plug is employed on heavy duty engines employing 85 high compression and high explosive pressures. By making the shell 1 relatively long and tightening the parts together in the manner described, I am enabled to obtain unusually strong and efficient pressure resisting plug without rendering the same unduly 90 heavy. In fact, the plug is but little heavier than the ordinary light duty plug now in common use, yet it is capable of withstanding the maximum pressures developed 95 in heavy duty engines.

100 In the foregoing detailed description and in the accompanying drawings, the invention has been set forth in its preferred, practical form, but I am aware that details of construction may be varied, for example, by the substitution of equivalents without departing from the spirit or substance of this invention, which is to be understood as broadly novel as is commensurate with the appended 105 claims.

110 Having thus fully described the invention, what I claim as new and desire to secure by Letters Patent is:

115 1. A spark plug embodying a shell, one end of which is exteriorly threaded to screw into the tapped hole of a cylinder, the other end of which shell is interiorly threaded, a shoulder formed interiorly of said shell and intermediate the ends thereof, an insulating member provided intermediate its ends with an enlarged portion adapted to seat on the interior shoulder of the shell, a valve seat member screwed into the interiorly threaded portion of the shell, and bearing against the enlarged portion of the insulating member to force it to a seat on the shoulder of the shell, 120 passages leading through the valve seat member, and through the enlarged portion of the insulating member, through which liquid may pass into the associated cylinder, 125 and a valve member threaded to engage with the interior threads of the shell, and formed to simultaneously seal or unseal all of the

passages when said valve is rotated into or out of engagement with the valve seat member.

2. A spark plug embodying a shell, one end of which is exteriorly threaded to screw into the tapped hole of a cylinder and the other end of which shell is interiorly threaded, a shoulder formed interiorly of said shell and intermediate the ends thereof, an insulating member provided intermediate its ends with an enlarged portion adapted to seat on the interior shoulder of the shell, a valve seat member screwed into the interiorly threaded portion of the shell and bearing against the enlarged portion of the insulating member to force it to a seat on the shoulder of the shell, passages leading through the valve seat member and through the enlarged portion of the insulating member, through which liquid may pass into the associated cylinder, and a cylindrical valve member threaded to engage with the interior threads of the shell and formed to simultaneously seal or unseal all of the passages when said valve is rotated into and out of engagement with the valve seat member, the interior of the cylindrical valve forming a basin adapt-

ed to contain the liquid to be passed through the plug into the cylinder.

3. A spark plug embodying a shell, one end of which is exteriorly threaded to screw into an engine cylinder, and the other end of which is interiorly threaded, an insulating member rigidly mounted within the shell and extending above the top thereof, a valve seat member cooperating with the interior threads of the shell and screwed thereinto, said valve seat member being provided with an integral sleeve embracing that portion of the insulating member within the shell and above the seat member, and a tubular valve also associated with the interior threads of the sleeve and cooperating with the valve seat member, the interior of said tubular valve forming a basin adapted to contain liquid to be introduced into the associated engine cylinder through the plug, the sleeve of the valve seat member serving to preclude the portion of the insulating member which it covers, from contact with such liquid.

In testimony whereof I have signed the foregoing specification.

EDWARD T. CURRAN.
